UNITED STATES PATENT OFFICE.

WILLIAM R. CLOER, OF LEGERWOD, NORTH CAROLINA.

JAR HOLDER.

Application filed April 14, 1923. Serial No. 631,992.

To all whom it may concern:

Be it known that I, WILLIAM R. CLOER, a citizen of the United States, residing at Legerwood, in the county of Mitchell and State of North Carolina, have invented certain new and useful Improvements in Jar Holders, of which the following is a specification.

In carrying out the present invention, it is my purpose to provide a highly improved form of jar holder, that is adapted for rigidly holding jars and the like in the application of the usual lids thereto for preventing the burning of the hands when the jars are hot, and for preventing the slipping of the same within the hand in the application of the lids thereto.

A further purpose of my invention is to provide a jar holder that will embrace the desired features of simplicity, durability and efficiency, the same comprising relatively few parts, and these so correlated as to reduce the liability of derangement to a minimum.

The nature and advantages of the invention will be better understood when the following detailed description is read in connection with the accompanying drawing, the invention residing in the construction, combination, and arrangement of parts as claimed.

In the drawing forming part of this application, like numerals of reference indicate similar parts in the several views, and wherein:

Figure 1—is a side elevation of my improved jar holder, the same being shown in position upon a jar.

Figure 2—is a top plan view thereof, and

Figure 3—is a perspective of one end of the gripping band, comprising this invention.

Referring to the drawing in detail, my device comprises a disk or plate 5 of relatively small dimensions to the marginal edge of which is pivotally secured at 6, the inwardly extending ends 7 of L-shaped arms 8. Riveted or otherwise suitably secured at 9, to the upper ends of these arms is a steel band 10, one end of the same being provided with a plurality of oblong openings 11. The opposite end of this band 10 is suitably secured at 12 to one end of one of a pair of crossed handles 13, the adjacent end of the

other member of this pair of crossed handles 13 being inwardly connected at 14, and adapted for engagement with any of the said openings 11 in the end of the band 10. These crossed handles 13, are, of course, pivotally secured together at 15, and in practice, a jar designated A in Figure 1 is positioned within the said band 10, legs 8 and upon the disk 5. Through an expansion of the handles 13, the hooked end 14 of one of the members thereof may be engaged with one of the said openings 11 in the adjacent end of the band 10, and by applying pressure to these handles, it will of course be understood that the band 10 will be contracted around the jar for rigidly holding the same.

Although I have herein shown and described the preferred embodiment of the present invention, it is nevertheless to be understood that minor changes may be made therein, without departing from the spirit and scope of the invention as claimed.

Having thus described my invention, what I claim as new, and desire to secure by Letters-Patent is:

A jar holder including a plate, a plurality of arms having one end pivotally secured to said plate and the other end formed with a lateral projection, a strip arranged in loop form and secured to the free ends of said lateral extensions, one end of said strip being provided with a plurality of openings, and a pair of pivotally connected operating members having the free end of one member pivotally connected to the other end of the strip, the corresponding free end of the other member being provided with a hook for engagement in the openings in the other end of said strip, whereby a jar may be positioned within the loop formed by said strip to rest on said plate, the hook formed on one of said members engaged in one of the openings of said strip with the members at a substantial angle to one another, said members being subsequently drawn toward each other to bring the lateral projections into tight gripping relation with the jar and move the arms on their pivots for bringing them in close relation to the sides and bottom of the jar to hold said sides in proper position within the looped strip.

In testimony whereof I affix my signature.

WILLIAM R. CLOER.
